UNITED STATES PATENT OFFICE.

GERALD L. WENDT, OF CHICAGO, ILLINOIS, ASSIGNOR TO STANDARD OIL COMPANY, OF WHITING, INDIANA, AND CHICAGO, ILLINOIS, A CORPORATION OF INDIANA.

REMOVAL OF SULPHUR AND SULPHUR COMPOUNDS FROM HYDROCARBON-OIL DISTILLATES.

No Drawing.

Application filed July 16, 1924. Serial No. 726,378.

The present invention relates to the removal of sulphur and sulphur compounds from hydrocarbon oil distillates, and particularly those such as pressure distillate and certain other stocks containing gasoline and kerosene fractions which are, in ordinary refinery practice, treated for the removal of sulphur and subsequently redistilled or rerun. It has particularly to do with the treatment of such oils, which, after the redistillation just referred to, become sour or show a reaction with "doctor".

It has now been found that the formation of products on redistillation which cause "sourness" of the oil and cause it to give the "doctor" reaction may be avoided in the following manner.

The oil, containing gasoline and heavier fractions, is treated in the usual manner with doctor solution; that is, with a solution of sodium hydroxide of about 10 to 20° Baumé saturated with litharge, and containing, if desired, a greater or less quantity of the precipitate or settling formed in the doctor solution by a previous treatment with oil. After this customary sweetening treatment, the treated oil is subjected to distillation, the temperature being carried to a maximum of 400° F., and preferably not higher than 350° F. In carrying out the distillation, the oil may be brought under atmospheric pressure conditions to the desired upper limit of temperature, say 350° F. As the distillation is continued, the temperature is held constant or, at least, not per-

mitted to rise above the predetermined maximum, and the pressure upon the distilling oil is reduced to cause its distillation or vaporization to continue. The reduction of pressure is continued until the desired products have been removed from the distilling oil without exceeding the predetermined maximum temperature. The amount of maximum vacuum required is dependent upon the character of the distillate product desired. Thus, for the removal of a gasoline-like product having a maximum boiling point of 425° F., a maximum vacuum of about 20 inches may be required. The distillate and residue formed by distillation under these conditions, with a maximum temperature not exceeding 400° F., and preferably 350° F., are found to be sweet and not to give the doctor reaction or the corrosion test for sulphur.

I claim:

The method of refining distillate oils containing products within the gasoline and kerosene boiling point range of the class hereinbefore described comprising treating such oils with doctor solution, and subsequently distilling the treated oil by bringing the oil under atmospheric pressure to a maximum temperature not exceeding 400° F., and continuing the heating of said oil with reduction of pressure and without exceeding said maximum temperature thereby causing its distillation to proceed.

GERALD L. WENDT.
